Max H. Ordway

UNITED STATES PATENT OFFICE.

HERMAN J. JAEGER, OF WEEHAWKEN, NEW JERSEY, ASSIGNOR TO JAEGER
RESEARCH LABORATORIES, INC.

METALLIC-FILAMENT LAMP.

Application filed September 22, 1920. Serial No. 411,941.

To all whom it may concern:

Be it known that I, HERMAN J. JAEGER, a citizen of the United States of America, residing at Weehawken, in the county of 5 Hudson and State of New Jersey, have invented certain new and useful Improvements in Metallic-Filament Lamps, of which the following is a specification.

This invention has reference to improvements in metallic filament lamps of the type which embody both a high and low candle power filament and has for its object to provide a construction which will considerably enhance the efficiency of the lamp.

According to this invention the lamp is provided with two low candle power filaments each carried in the usual manner by an outer lead and both connected in the focal centre to a central metallic anchor in form 20 of a coiled wire which is adapted at times to serve merely as lead and at others to act as a third filament to produce in conjunction with the lateral filaments high candle power.

For low candle power either one of the 25 two lateral filaments is thrown into circuit, whereby the possibility is given to continue the use of the lamp when one of the filaments is burnt out.

For high candle power both lateral filaments are thrown into circuit whereby the 30 central wire is converted into a third filament, still more increasing the candle power.

In the accompanying drawing in which similar reference characters denote corresponding parts, Fig. 1 is an elevation partly 35 in section of my new lamp; Figs. 2 to 4 are diagrammatic illustrations of the electric connections, Fig. 2 showing the right hand filament with the central filament being in 40 circuit for low candle power; Fig. 3 showing the left hand filament with the central filament being in circuit for low candle power, and Fig. 4 showing the two side filaments and central filament being in circuit 45 for high candle power.

Referring to the drawing more in detail, *a* represents the globe, *b* the stem or support; *c*, *d* and *e* denote the leads which pass through the stem *b* parallel to each other 50 and connect with short platinum wires *c'*, *d'*, *e'* respectively in the usual manner. The other ends of these platinum wires are connected to fine conductive tubes *f*, *g*, *h* respectively, fused into the solid portion of 55 the stem *b*. Conductively connected to the

outer end of the tubes are three concentrated or coiled metallic wires *i*, *j* and *k* of which the wire *j* forms a rectilinear extension of the central tube *g* terminating in the focal centre of the globe and serving normally as 60 anchor for the two other wires *i* and *k* which converge from their respective tubes *f*, *h* toward the focal centre and there are conductively connected to one another and to the wire *j*. The outer or lateral wires *i*, *k* 65 are of uniform thickness and serve each for low candle power, while the central wire *j* is made of different thickness, so that when either one of the lateral wires is thrown into circuit to produce low candle power, said 70 central wire will act merely as conductor, but when both lateral wires are thrown into circuit, it will be converted into a third filament which, in conjunction with said lateral wires, will produce high candle power. 75

This construction enables the use of the lamp with either one of the lateral filaments for low candle power, so that when one is burnt out the other is still available. Furthermore, it also affords an economical utilization of the current by the arrangement 80 of the third wire capable of acting at times as conductor and at others as filament.

What I claim and desire to secure by Letters Patent is:

1. In a metallic filament lamp, the combination with the globe and three parallel leads, of three metallic wires extending from said leads and conductively connected to one another in the focal centre of the globe, the 90 outer wires forming filaments of uniform resistance each to produce low candle power and the middle wire being of such resistance that when either of the outer filaments is thrown into circuit, said middle wire will act 95 merely as lead and when both lateral filaments are thrown into circuit it will act as a third filament producing in conjunction with the same high candle power.

2. In a metallic filament lamp, the combination with the globe and three parallel leads, of three metallic wires extending from said leads of which the middle one extends rectilinearly with its respective lead and terminates in the focal centre, and the lateral ones converge toward and are conductively connected to one another and to said middle wire in said focal centre, the outer wires constituting filaments of uniform resistance to serve each for low candle power 110

and the middle wire being of such resistance as to act merely as lead when either one of the lateral filaments is thrown into circuit, but to act as additional filament when both 5 said lateral filaments are thrown into circuit so as to produce in conjunction with them high candle power.

In testimony whereof I affix my signature in presence of two witnesses.

HERMAN J. JAEGER.

Witnesses:
